(57) **CLAIM**

The ornamental design for a golfing accessory tool, as shown and described.

DESCRIPTION

FIG. 1 is a front left side perspective view of a golfing accessory tool;

FIG. 2 is a front right side perspective view of the golfing accessory tool;

FIG. 3 is a front view of the golfing accessory tool with an unclaimed hook in a secured position;

FIG. 4 is a rear view thereof;

FIG. 5 is top view thereof;

FIG. 6 is bottom view thereof;

FIG. 7 is a left side view thereof;

FIG. 8 is a right side view thereof;

FIG. 9 is a front right side perspective view thereof with a ball marker in a detached position;

FIG. 10 is a front right side perspective view thereof with a ball marker in a secured position; and,

FIG. 11 is a right side view thereof with a ball marker in a secured position.

The broken lines in the drawings depict environmental subject matter and form no part of the claimed design.

1 Claim, 6 Drawing Sheets
